UNITED STATES PATENT OFFICE.

PERCY D. HEDDERWICK, OF ACTON, COUNTY OF MIDDLESEX, ENGLAND.

BRAKE FOR VELOCIPEDES.

SPECIFICATION forming part of Letters Patent No. 393,230, dated November 20, 1888.

Application filed June 26, 1888. Serial No. 278,214. (No model.) Patented in England December 24, 1887, No. 17,745; in France June 2, 1888, No. 190,984, and in Belgium June 13, 1888, No. 82,176.

To all whom it may concern:

Be it known that I, PERCY DAVID HEDDERWICK, a citizen of England, residing at 10 Heathfield Road, Acton, in the county of 5 Middlesex, England, have invented a new and useful Improvement in Brakes for Velocipedes and other Vehicles, (for which I have obtained 10 patents in France, dated June 2, 1888, No. 190,984; in Belgium, dated June 13, 1888, No. 10 82,176, and have made application for patent 15 in Great Britain, dated December 24, 1887, No. 17,745,) of which the following is a specification.

When a flexible strap is drawn close round 15 the brake-drum of a velocipede or other vehicle, in order to retard or stop its revolution, this is usually done by pulling the one end of the strap while the other end remains fixed. Although this is effective when the drum 20 revolves in the one direction, it is apt to be inefficient when the drum revolves in the opposite direction, as the friction in that case tends to draw the strap in opposition to the pull applied to it, and so loosens the brake.

25 My invention relates to means of connecting and working the brake-strap in such a manner that it is efficient whether the brake-drum revolves in the one direction or the other. For this purpose I connect both ends 30 of the brake-strap to the brake lever or pull in such a manner that when this lever or pull is moved, straining the strap, only one end of the brake-strap is moved by it, the other end being drawn and made to bear against a fixed 35 stop by the friction of the strap on the drum acting in the direction of the drum's revolution. Each end of the strap being thus provided with a stop according as the drum revolves in the one direction or the other, the 40 one or the other end of the brake-strap becomes for the time a fixture, while the other end of the brake-strap is moved with the brake lever or pull away from its stop, tightening the brake.

45 Figures 1, 2, and 3 of the accompanying drawings are diagrams illustrating my improvements; and Figs. 4, 5, and 6 are side views of parts of brake drums or wheels, with several modified arrangements, according to my

invention, of the connections to the brake- 50 strap.

In these figures the same reference-letters are employed, as far as possible, to indicate corresponding parts.

A is the brake wheel or drum.

B is the flexible brake-strap having its two ends, C and D, which usually are pin-joints, serving to connect the strap to the fixed stop and to the pull, respectively. As indicated in Fig. 1, the two ends C and D are connected together by a chain or flexible band, E, passing over a pulley mounted on the pull P. According as the drum A revolves in the one direction or the other the one or the other of the two pins C or D is brought against a fixed 65 stop, c or d, the other of the two pins being drawn away from its stop by the strain of the pull P. As indicated in Fig. 2, the two ends C and D of the brake-strap are jointed to two arms of a T-lever, F, to the third arm of which 70 the pull P is connected. Instead of a T-lever, a straight lever may be used, as indicated by the dotted lines F'. As indicated in Fig. 3, the two ends of the brake are attached to the 75 ends of a lever, L, having the pull P attached to its middle.

In the arrangement shown in Fig. 4, instead of a pull, a pushing-rod, P, is jointed to the long arm of the T-lever F, and the brake-strap is jointed to its short arms at C and D. The 80 stop for C is at the end c of a slotted hole in the supporting-frame G, and the stop for D is at the edge of the frame at d.

In the arrangement shown in Fig. 5 the pull P is jointed to about the middle of a lever, L, 85 the one end of which is connected by a link, H, to the one end, D, of the brake-strap, the other end being jointed to one arm of a lever, K, which is pivoted at k on the fixed frame G. The other arm of the lever K is jointed to the 90 end C of the brake-strap, and the lever K has a tail which abuts at c on the tubular part V of the fixed frame, this abutment constituting the stop for the end C of the brake-strap. The pin D finds its stop at d, the end of a slotted 95 hole in the frame G.

In the arrangement shown in Fig. 6 the pull P is jointed to about the middle of a bent

lever, L, one arm of which is connected by a link, H, to the brake end D, the other arm by a link, M, to a strap, N, which passes partly round the tubular part V of the frame and is jointed to the brake end C. The stops for C and D are respectively the ends c and d of slotted holes in the fixed frame G.

Although I have shown arrangements of brakes of a form suitable for velocipedes, modified arrangements might be made suitable for other vehicles.

Having thus described the nature of my invention and the best means I know for carrying the same into practical effect, I claim—

15 In a brake for a velocipede or other vehicle, a flexible brake-strap having both its ends con-

nected to the brake pull or lever, in combination with a fixed stop for each of these ends, substantially as and for the purpose set forth.

In testimony whereof I have signed my name ²⁰ to this specification, in the presence of two subscribing witnesses, this 11th day of June, A. D. 1888.

P. D. HEDDERWICK.
